COUNTERBALANCE

Leland F. Burnham, Houston, Tex., assignor to
 Emoco Derrick & Equipment Company, Los
 Angeles, Calif., a corporation of California

Application May 26, 1939, Serial No. 275,881

16 Claims. (Cl. 74—590)

My invention relates in general to counterbalances for swinging beams and relates in particular to a counterbalance for a walking beam, such as used in well pumping equipment.

5 In pumping equipment of this general type it is customary to support a walking beam by means of a bearing disposed at the upper end of a Samson post, the string of sucker rods being connected to the front end of the walking beam, 10 and the pitman for reciprocating the walking beam and the counterbalance for balancing the load on the walking beam being connected to the rear end of the walking beam. In some types 15 of equipment, the counterbalance is connected to the walking beam crank which operates the pitman so as to rotate therewith, while in other types of equipment the counterbalance comprises weights mounted directly upon the walking beam. The present invention relates to this latter type 20 of counterbalance construction.

It is an object of the invention to provide a counterbalance comprising a plurality of weight members which may be secured in desired number on the rearward portion of the walking beam 25 and which are applied to the beam in interlocking arrangement. A feature of the present construction is that the weight members are positively held against the inner face of a permanently secured abutment part of the walking beam.

30 It is known that there are types of counterbalance construction in which the weights are secured to a beam by means of clamps or bolts, and it has been found that where such types of 35 construction have been employed the loosening of bolts or clamps will result in the weight parts being thrown from the walking beam.

It is an object of the present invention to provide a counterbalance construction wherein the 40 weight members may be placed on the walking beam by moving them inward from positions at the sides of the beam and to provide such weight members with cooperating overlapping portions having means of interengagement when the 45 weight members are in place on the beam, such means of interengagement preventing removal of the weight members from the beam in lateral direction without first separating the weight members by suitable movement of one or more 50 of them longitudinally along the beam.

A further object of the invention is to provide 55 a weight member which is so formed that it may be applied to the walking beam from either side thereof, and when so applied will overlap and interlock with a weight member of like

form applied to the beam from the other side thereof.

A further object of the invention is to provide 5 a counterbalance beam construction wherein the beam is provided with a permanently secured abutment at or near the end thereof, such abutment providing a face lying in a plane substantially perpendicular to the longitudinal axis of the walking beam, against which abutment the weight members may be assembled and which 10 abutment will prevent throwing of the weight members from the end of the beam.

A further object is to provide a counterbalance construction wherein an assembly of cooperating 15 weight members is applied to the walking beam, and through which weight members bolts may be passed to secure the weight members in a compact assembly, and, if desired, to hold the weight members against the abutment of the walking beam. The arrangement of the cooperating parts 20 is such that loosening or loss of a bolt will not result in the weight members being thrown from the walking beam.

An object of the invention is to provide a weight 25 member which may be conveniently employed in multiple arrangement on a walking beam so as to provide a counterbalance of desired size by merely placing a suitable number of the cooperating weight members on the beam.

A further object of the invention is to provide 30 a weight member, adapted to be used in multiple with other weight members of like form, such weight member having a body portion to lie adjacent a side of the walking beam and having parts extending therefrom so as to pass across 35 the upper and lower faces of the walking beam. Such laterally extending parts are referred to as plates or wings and in the preferred practice of the invention have a thickness equal to substantially half the thickness of the body of a weight 40 so that when the wings are placed in overlapping face to face engagement on a beam they will substantially occupy a space defined by the planes of the front and rear faces of the body of a weight member.

A further object of the invention is to provide 45 a weight member having cooperating lugs and recesses so formed thereon that when a pair of such weight members are placed in overlapping arrangement from opposite sides of a walking 50 beam, the lugs and recesses of the weight members will interengage and prevent lateral movement of such weight members.

Further objects referring to the drawing:

Fig. 1, is a fragmentary elevation showing a 55

counterbalance walking beam in accordance with my invention.

Fig. 2 is a view of the right end of the structure shown in Fig. 1.

5 Fig. 3 is an enlarged fragmentary section taken on a plane indicated by the line 3-3 of Fig. 1.

Fig. 4 is an enlarged cross-section taken as indicated by the line 4-4 of Fig. 1.

10 Fig. 5 is an enlarged sectional view taken as indicated by the line 5-5 of Fig. 1.

Fig. 6 is an enlarged perspective view of a weight member made in accordance with the invention.

In Fig. 1 I show the rear end of a walking beam 10 having a stirrup 11 provided with openings 12 by which a pitman rod may be connected to the walking beam 10 to reciprocate the same. At the rear end of the walking beam 10 there is a counterbalance 13 comprising an assembly of 20 cooperating weights 14 and 14' having the general form shown in perspective in Fig. 6.

Each weight member is of rectangular form with a notch 15 extending inward from a side thereof, the height of such notch being substantially the same as the height of the walking beam 10. In the preferred practice of the invention, the beam 10 comprises a structural I-beam having a web 16 and projecting flanges 17. Where the beam 10 comprises such I-beam, 30 slots 18 are extended from the bottom of the notch 15 to receive flanges 17 when the weight member 14 is applied to the beam 10. Each weight member 14 has a body 20 to lie adjacent a side of the beam 10, and from the upper and lower ends of the body 20 plates or wings 21 are extended so as to lie above and below and define the notch 15. These wings 21 are preferably formed so that the rear face thereof will be co-planar with the rear face of the body 20, and the thickness t of each wing is substantially 40 half the thickness T of the body 20. The body 20 of each weight 14 has a bolt opening 22 therethrough as shown in Figs. 3 and 4 and the body 20 of each weight 14' has a notch therein as shown in Figs. 4 and 6. A lug 23 projects from the front face of each wing 21, adjacent the body 20. Each wing 21 is likewise provided with a recess 24 disposed near the unsupported end thereof or remote from the body 20. The 50 lugs 23 are preferably conoidal and the recesses 24 may be conoidal openings which pass through the wings 21.

As best shown in Fig. 4, an abutment plate 26 is welded adjacent the end of the beam 10. As 55 shown in Fig. 2, this abutment plate 26 is rectangular in form and has an I-shaped opening 27 so that it may be slipped on to the end of the beam 10 a sufficient distance to expose the extreme end 28 of the beam 10. Welds 29 and 30 are then applied to secure the plate permanently to the beam 10 in a position wherein the inner face of the plate 26 lies in a plane substantially 60 perpendicular to the longitudinal axis of the walking beam 10.

65 A plurality of weight members 14 and 14' are employed in the counterbalance 13, such weight members being employed in pairs, one member of each pair being moved into position on the walking beam 10 from one side thereof and the other 70 member of the pair being moved into position on the walking beam from the other side thereof. When a weight member 14 is rotated on a vertical axis through an angle of 180° from the position of the weight member shown in Fig. 6, 75 such second weight member may be placed in

overlapping relation to the first weight member, with the front faces of the cooperating wings in engagement, and with the lugs 23 projecting into the recesses 24, as clearly shown in Fig. 5 where-in five pairs of weight members are shown assembled upon the beam 10. When the weight members 14 are assembled, as shown, the bolt holes 22 and the notches 38 will be aligned so that tie bolts 35 may be passed therethrough. The tie bolts 35 also pass through openings 37 10 in the abutment plates 26 and preferably have lock-nuts 36 on the ends thereof. By use of the tie bolts 35, the assembly of weight members 14 will be clamped tightly against the inner or left- 15 ward face of the abutment plate 26.

The notches or slots will make it possible to remove or install one or more pairs of weight members without removing the tie bolts 35. Should it be desired to remove a pair of the weight members 14' to reduce the weight of the 20 counterbalance 13, the tie bolts 35 may be loosened sufficiently to permit separation of adjacent weight members 14 to provide sufficient space for disengagement of the lugs 23 from the recesses 24 of the cooperating pair of weight 25 members 14' which are to be removed. The reverse of this procedure may be used when it is desired to add weight members 14 to the assembly forming the counterbalance 13.

I have herein shown a simple and practical 30 embodiment of my invention. Variations in form and arrangement may be employed without departing from the principles of the invention; therefore, the invention is not limited to the details hereinbefore described but should be ac- 35 cording the full scope of the appended claims.

I claim as my invention:

1. In a counterbalance for a beam of the character described, the combination of: an abutment securable to the rearward portion of 40 the beam; and a counterweight element to be placed adjacent the inner face of said abutment comprising weight members formed so as to be placed on said beam from opposite sides thereof, each of said weight members having an upper 45 wing which extends across the upper face of said beam and a lower wing which extends across the lower face of said beam, said weight members having parts which interlock so as to prevent lateral movement of said weight members when 50 the same are in face to face engagement on said beam.

2. In a counterbalance for a beam of the character described, the combination of: an abutment securable to the rearward portion of the 55 beam; and a counterweight element to be placed adjacent the inner face of said abutment comprising weight members formed so as to be placed on said beam from opposite sides thereof, each of said weight members having a body which lies 60 adjacent a side of said beam, an upper wing which extends across the upper face of said beam, and a lower wing which extends across the lower face of said beam, said wings each being substantially half the thickness of said body, and 65 said weight members having parts which interlock so as to prevent lateral movement of said weight members when the same are in face to face engagement on said beam.

3. In a counterbalance for a beam of the character described, the combination of: an abutment securable to the rearward portion of the beam; and a counterweight element to be placed adjacent the inner face of said abutment comprising weight members formed so as to be 75

- placed on said beam from opposite sides thereof, each of said weight members comprising a body to rest adjacent a side of said beam, said body having a front face and a rear face and having an upper wing to extend across the upper face of said beam, and a lower wing to extend across the lower face of said beam, each of said wings having a rear face substantially coplanar with the rear face of said body and each wing having a thickness substantially half that of said body so that when said weight members are placed on said beam from opposite sides thereof the wings thereof will lie in overlapping engagement and occupy the space defined by the planes of the front and rear faces of the bodies of said weight members.
4. In a counterbalance for a beam of the character described, the combination of: an abutment securable to the rearward portion of the beam; and a counterweight element to be placed adjacent the inner face of said abutment comprising weight members formed so as to be placed on said beam from opposite sides thereof, each of said weight members comprising a body to rest adjacent a side of said beam, said body having a front face and a rear face and having an upper wing to extend across the upper face of said beam, and a lower wing to extend across the lower face of said beam, each of said wings having a rear face substantially coplanar with the rear face of said body and each wing having a thickness substantially half that of said body so that when said weight members are placed on said beam from opposite sides thereof the wings thereof will lie in overlapping engagement and occupy the space defined by the planes of the front and rear faces of the bodies of said weight members, each of said bodies having cooperating projections and recesses which interlock when said bodies are in face to face position on said beam so as to resist removal of said bodies from said beam.
5. In a counterbalance for a beam of the character described, the combination of: an abutment securable to the rearward portion of the beam; and a counterweight element to be placed adjacent the inner face of said abutment comprising weight members formed so as to be placed on said beam from opposite sides thereof, each of said weight members comprising a body to rest adjacent a side of said beam, said body having a front face and a rear face and having an upper wing to extend across the upper face of said beam, and a lower wing to extend across the lower face of said beam, each of said wings having a rear face substantially coplanar with the rear face of said body and each wing having a thickness substantially half that of said body so that when said weight members are placed on said beam from opposite sides thereof the wings thereof will lie in overlapping engagement and occupy the space defined by the planes of the front and rear faces of the bodies of said weight members, each of said wings of said bodies having a projecting lug and a recess on the front thereof so positioned that when two of said weight members are placed in overlapping position with the front faces of said wings in engagement, the said lugs and recesses will interengage.
6. In a weight member to be used in multiple in a counterweight for a walking beam, the combination of: a body adapted to lie adjacent a side of the beam; and upper and lower wing members extended laterally from the upper and lower ends of said body so as to extend across the upper and lower faces of said beam, said wing members being substantially half the thickness of said body so that when a number of said weight members are placed on said beam in alternate order from opposite sides of the beam, said wing members will lie in overlapping arrangement and adjacent of said bodies will be in face to face engagement.
7. In a weight member to be used in multiple in a counterweight for a walking beam, the combination of: a body adapted to lie adjacent a side of the beam; and upper and lower wing members extended laterally from the upper and lower ends of said body so as to extend across the upper and lower faces of said beam, said wing members being substantially half the thickness of said body so that when a number of said weight members are placed on said beam in alternate order from opposite sides of the beam, said wing members will lie in overlapping arrangement and adjacent of said bodies will be in face to face engagement, said wing members having cooperating shoulders so that when a plurality of said weight members are arranged on said beam, shoulders on the wing members of one of said weight members will cooperate with the shoulders of the wing members of the adjacent weight member to prevent movement of the adjacent weight members apart in a direction transverse to the longitudinal axis of the beam.
8. In a weight member to be used in multiple in a counterweight for a walking beam, the combination of: a body adapted to lie adjacent a side of the beam; and upper and lower wing members extended laterally from the upper and lower ends of said body so as to extend over the upper and lower faces of said beam, said wing members having cooperating shoulders for engagement with the cooperating shoulders of a like wing member when a pair of weight members are placed on said beam from opposite sides thereof, said shoulders being disengageable only by relative movement of said weight members in a direction lengthwise of said beam.
9. In a counterbalance for a beam of the character described, the combination of: an abutment near the end of said beam; an assembly of vertical weight members slidable on said beam so as to form a stack resting against said abutment; bolt means passing through said weight members to hold them to said abutment, said bolt means being releasable so that said weight members may be separated; and an insertable weight member adapted to be inserted sidewardly in said assembly of weight members and to be clamped therein, said insertable weight member having a slot therein to receive said bolt means.
10. In a counterbalance for a beam of the character described, the combination of: an abutment near the end of said beam; an assembly of weight members slidable on said beam so as to form a stack resting against said abutment; bolt means passing through said weight members to hold them to said abutment, said bolt means being releasable so that said weight members may be separated; and an insertable weight member adapted to be inserted in said assembly of weight members and to be clamped therein, said insertable weight member having a body to rest adjacent a face of said beam and laterally extending members to extend across opposite faces of said beam.
11. In a walking beam counterbalance of the character described, the combination of: a walk-

ing beam having secured to it near the end thereof an abutment with an inwardly faced shoulder; and a plurality of weight members on said walking beam in consecutive order adjacent said inwardly faced shoulder of said abutment, said weight members being in face to face engagement and the first of said weight members lying against said shoulder which functions to prevent movement of said weight member off the end of said walking beam when the same is in motion.

12. In a walking beam counterbalance of the character described, the combination of: a walking beam having secured to it near the end thereof of an abutment with an inwardly faced shoulder; and a plurality of weight members on said walking beam in consecutive order adjacent said inwardly faced shoulder of said abutment, said weight members being in face to face engagement and the engaging faces thereof have cooperating projections and depressions to prevent relative movement of the engaging weight members in a direction transverse to the length of the walking beam, and the first of said weight members lying against said shoulder which functions to prevent movement of said weight member off the end of said walking beam when the same is in motion.

13. In a weight member to be used in multiple in a counterweight for a walking beam, the combination of: a portion adapted to lie adjacent a face of said beam; and portions extending laterally from the ends of said first named portion so as to straddle said beam, said weight member being so formed as to be placed on said beam in side-by-side relation to similarly formed weight members, and said weight member having a shoulder thereon to engage a shoulder on an adjacent weight member so as to prevent relative movement of the thrust engaging weight members in a direction transverse to said beam.

14. In a weight member to be used in multiple

in a counterweight for a walking beam, the combination of: a body adapted to lie adjacent a side of the beam; and upper and lower wing members extended laterally from the upper and lower ends of said body so as to extend across the upper and lower faces of said beam, said wing members being so formed that when a number of said weight members are placed on said beam in alternate order from opposite sides of the beam, said wing members will lie in overlapping face to face engagement, said wing members having cooperating shoulders so that when a plurality of said weight members are arranged on said beam, shoulders on the wing members of one of said weight members will cooperate with the shoulders of the wing members of the adjacent weight member to prevent movement of the adjacent weight members apart in a direction transverse to the longitudinal axis of the beam.

15. In a walking beam counterbalance of the character described, the combination of: a plurality of vertical weight members each having a body and a laterally extending wing, said weight members being assembled on opposite sides of the walking beam from a sideward direction and with said bodies on opposite sides and said wings extending laterally across the top of said walking beam, the wings of opposite weight members being nested together; and means for holding said wings in interengagement.

16. In a walking beam counterbalance of the character described, the combination of: a plurality of vertical weight members each having a body and a laterally extending wing, said weight members being assembled on opposite sides of the walking beam from a sideward direction and with said bodies on opposite sides and said wings extending laterally across the bottom of said walking beam, the wings of opposite weight members being nested together; and means for holding said wings in interengagement.

LELAND F. BURNHAM.
